UNITED STATES PATENT OFFICE

EDWARD A. TANGENBERG, OF GRAND RAPIDS, MICHIGAN

HINGE

Application filed April 26, 1929. Serial No. 358,377.

This invention appertains to hinges and more particularly to hinges of the type embodying a support associated therewith, so that the hinge will act as means for limiting

5 the swinging movement of the leaves of the hinge relative to one another and for supporting a device to which one of the leaves is connected.

One of the primary objects of this invention is to provide a novel desk hinge, which is so constructed as to fully support a lid of a desk in a fully open position flush with the bed of the desk so as to permit said lid to be used as a writing surface, the leaf of 15 the hinge being countersunk in the edge of the lid so as to permit the entire top surface to be used as a writing portion.

Another important object of my invention is the provision of a hinge having a toggle, 20 forming a support, hingedly connected to the leaves of the hinge, the toggle being so arranged as to rest on the hinge itself when the lid of the desk is open in horizontal position flush with the bed of the desk, the bearing surface of the toggle seating on the edge of the toggle and not at the ends thereof.

A further object of my invention is the provision of a combination support and hinge embodying a pair of flat leaves arranged at right angles to one another pivotally connected together at their inner ends by means of a rivet or pivot pin, with a toggle connected to the leaves on each side of the pivot point thereof through the 35 medium of suitable pivot ears formed directly on said leaves.

A still further object of my invention is to provide an improved combination hinge and support of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawing, in which drawing:

50 Figure 1 is a perspective view of my im-

proved hinge showing the same applied to a fragment of a desk and illustrating the position of the hinge when the desk lid is in its raised position.

Figure 2 is a similar view illustrating 55 the position of the hinge when the desk lid is in its fully open position.

Figure 3 is a top plan view of the hinge showing the same in its fully open position.

Figure 4 is a detail transverse section 60 through the hinge taken on the line 4—4 of Figure 3 looking in the direction of the arrows, and

Figure 5 is a detail transverse section 65 through the hinge taken on the line 5—5 of Figure 3 looking in the direction of the arrows.

Referring to the drawing in detail, wherein similar reference characters designate corresponding parts throughout the 70 several views, the letter A generally indicates my improved hinge and B a desk with which the same can be associated. I have only shown a fragment of the desk B and the same includes the swinging lid 10 and 75 bed 11 to which the lid is adapted to be connected by means of my novel hinge.

My hinge A comprises leaves 15 and 16 which are preferably formed from flat sheet metal and the leaf 15 is preferably disposed flat in a horizontal plane while the leaf 16 is disposed on edge in a vertical plane, so that the leaf 15 can be secured to the top face of the bed 11, as clearly shown, and the leaf 16 secured to the edge of the lid 10, as 80 shown. These leaves are preferably countersunk respectively in the top face of the bed and in the side edge of the lid, suitable screws 17 being employed for holding the leaves in place. The forward end of the leaf 15 has formed on its side edge a depending 85 ear 18 which can be likewise countersunk in the side edge of the bed 11 if preferred.

This ear projects slightly beyond the forward edge of the leaf 15 and is arranged in 90 overlapping relation with the pivot ear 19 formed on the inner end of the leaf 16. The ears 18 and 19 are connected together by a rivet or pivot pin 20 which permits the free 95 swinging of the leaves relative to one another. 100

other. Each leaf has formed thereon intermediate the ends thereof upstanding pivot ears 21 and 22 respectively and it can be seen that the pivot ears 21 is turned at 5 right angles to the body portion of the leaf, while the pivot ear 22 forms a substantial continuation or extension of the upper edge of the leaf 16. The pivot ears 21 and 22 form means for permitting the connection of the toggle support 23 with the leaves and this toggle includes links 24 and 25 which are pivotally connected together at their rear ends by the use of a suitable rivet or pivot pin 26. The rear end of the link 24 10 is pivotally connected to the ear 21 by the use of a suitable rivet or pivot pin 27, while the forward end of the link 25 is connected to its ear 22 by the use of a suitable rivet or pivot pin 28. The forward end of the link 25 is slightly offset as at 29 so that the main 15 portion of the link will lie directly above the upper edge of the leaf 16 and thus abut the same when the lid 10 is in its fully open position, as will be later described. The rear end of the link 24 is also slightly offset 20 as at 30 so that the body portion of this link will lie within the plane of the outer edge of the leaf 15 and thus abut the top surface of the leaf when the lid is in its fully open 25 position. It is to be also noted at this point that the meeting points of the links 24 and 25 at their lower edges are cut away or notched as at 31 so as to receive the ears 18 and 19 when the lid is in its extreme lowered 30 position.

The hinge is connected to the bed and lid 10 as shown and when the lid is swung to its lowered position the lower edges of the links 24 and 25 of the toggle 23 will abut and 35 bear against the top face of the leaf 15, and the top edge of the leaf 16 and thus limit the downward swinging movement of the lid 10 below a horizontal plane and thereby effectively support said lid in a correct open 40 position so that the same can be used as a writing surface. By having the links of the toggle abut the leaves of the hinge, a complete bearing surface is formed along the entire lower face of the toggle when 45 the same is in its complete open position, thus forming an efficient and steady means for supporting the lid.

From the foregoing description, it can be seen that I have provided a novel and 50 simple form of hinge which will effectively act as a support for a desk lid when the same is in its open position and which will permit the swinging of the lid to an open 55 position in a horizontal plane flush with the bed of a desk.

Changes in details may be made without departing from the spirit or scope of this invention, but:

What I claim as new is:

65 A combined hinge and support comprising

a pair of leaves each including a flat body plate, one of which is arranged in a horizontal plane and the other in a vertical plane, a depending pivot ear formed on one longitudinal edge of the body plate arranged in a horizontal plane at the inner end thereof and projecting forwardly therefrom at right angles thereto, a rearwardly extending pivot ear formed on the inner end of the leaf arranged in a vertical plane, a pivot connecting the ears together, a pivot ear formed on the mentioned edge of the body plate arranged in a horizontal plane and extending upwardly therefrom at right angles thereto, a pivot ear formed on the upper edge of the other body plate and extending upwardly therefrom, said last mentioned ears being arranged equidistantly from the pivot point of said leaves, a toggle including a pair of links pivotally connected together at their inner ends, and means pivotally connecting the outer ends of said links to the last mentioned ears, the outer ends of said links being offset laterally and the inner ends of said links being offset upwardly defining a notch in the lower edge of the leaves when the hinge is in its fully opened position for receiving the first mentioned pivot ears of the body plates to permit bearing engagement of the lower edges of the links with the leaves when the hinge is in its fully opened position.

In testimony whereof I affix my signature.

EDWARD A. TANGENBERG.
